UNITED STATES PATENT OFFICE.

ELMER E. HAND, OF NEW YORK, N. Y.

APPARATUS FOR EXTRACTING ESSENCE.

SPECIFICATION forming part of Letters Patent No. 768,575, dated August 23, 1904.

Application filed August 11, 1903. Serial No. 169,181. (No model.)

To all whom it may concern:

Be it known that I, ELMER E. HAND, a citizen of the United States, residing in the borough of Manhattan, city, county, and State 5 of New York, have invented certain new and useful Improvements in Apparatus for Extracting Essences, of which the following is a specification.

My invention relates to an apparatus for 10 extracting essences; and it consists in the construction hereinafter described and claimed.

In the accompanying drawings I have shown 15 an essence-extractor embodying one form of my invention.

15 In the drawings, Figure I is a horizontal sectional elevation of the extractor. Fig. II is an end view of the still, and Fig. III is a section on line III-III of Fig. II.

In the drawings, *a* indicates a suitable tank 20 capable of withstanding high pressure. This tank is preferably mounted on a suitable foundation *b* and is herein shown as having condensing devices consisting of a dome *c* and a condenser-hood *d*. A suitable valve apparatus *e* may be employed for the purpose of 25 controlling the flow of vapors into the condenser-hood.

Mounted upon a suitable shaft *f* and located 30 within the still is a foraminous or perforated drum *g*, preferably provided with a hinged portion *h*, forming a door. The shaft *f* passes through a stuffing-box *i* at one end of the still and is extended laterally to the left of the figure for some distance on the outside of the 35 still, so as to permit the drum to be removed from the still, the shaft *f* sliding in the stuffing-box *i*. At the other end of the still I provide a removable head. (More clearly shown in Fig. II.) This removable head and 40 its fastening may be described as follows:

Riveted or otherwise suitably secured to the shell of the still *a* is a ring *k*. This ring is provided with an interrupted screw *l*. (Indicated in dotted lines in Fig. II.) The upper 45 face of the ring *k* is recessed at *m*, and a suitable packing-ring or gasket *n* is preferably seated in the said annular recess. The shell of the still is also preferably surrounded at its end by a hoop *p* for the purpose of adding 50 to the rigidity and strength of the still at the

end where the removable head is located. Seated in the ring *k* is a strong removable head *o*, provided with a stuffing-box *r*, through which the shaft *f* passes. The head is similarly provided with an interrupted screw corresponding to the interrupted screw of the ring *k*.

A suitable lip *s* is preferably formed on the head, which lip when the head is in position will enter the recess *m* and bear upon the 60 packing or gasket *n*. This packing or gasket makes a tight joint, which joint is in addition to any joint that may be formed by the interrupted screw.

The shaft *f* is preferably carried in bearings *t*, mounted upon a suitable truck or trave- 65 ller *u*. I also preferably carry upon the truck a source of motive power, (herein shown as an electric motor *v*), from which motion may be transmitted to the shaft *f* in any suit- 70 able manner.

I have shown herein one means consisting of trains of gearing *w* and *x* and a counter-shaft *y*, transmitting motion from the shaft *z* of the motor *v* to the shaft *f* of the still. I 75 have also shown suitable steam-inlet pipes 1 and 2 and a waste-outlet pipe 3. It will be understood, however, that in giving these various details I do not mean to limit myself thereto.

The mode of operation is as follows: Let 80 us suppose that the parts are in the position shown in Fig. I of the drawings and that the revolving cylinder or cage is without a charge. The head of the still is given a partial rotation, so as to disengage the interrupted screw 85 and joint, and the entire structure is there- upon backed away from the still, the shaft *f*, sliding freely in the stuffing-box *i* at the closed end of the still. The charge is now placed in the revolving cylinder or cage and 90 the cylinder or cage run into the still and the head *o* reseated again. Steam or other vapor or gas is now introduced through the pipes 1 or 2, or both of them. In the manu- 95 facture of witch-hazel the charge in the cage is witch-hazel wood or brush, and the fluid medium employed for the distillation is steam. The motor *v* is started and the cage revolved, so as to give the steam an opportunity to reach every part of the mass under treatment. 100

The steam and vapor laden with the extract pass over to the condenser-hood and are there condensed and are received in a suitable receptacle, which is not shown herein.

5 Having described my invention, what I claim, and desire to secure by Letters Patent, is:

1. In an apparatus for obtaining extracts, the combination of a stationary still, a rotary cage within said still, a shaft projecting beyond each end of the cage, one of said shaft ends being mounted to revolve and slide in the end of the still, a removable head at the opposite end of the still, and means for revolving the cage and sliding it laterally out of the still while supported by one of said shafts.

2. In an apparatus for obtaining extracts, the combination of a stationary still, a porous cage within the still, a shaft projecting beyond each end of the cage, one of said shaft ends extending through the end wall of the

still, a removable head at the opposite end of the still, a laterally-moving truck, and mechanism mounted upon said truck for revolving 25 said cage, said truck adapted to be moved to withdraw the cage from the still, substantially as described.

3. An apparatus for obtaining extracts, comprising a stationary still, a dome at the top of 30 said still, a condenser-hood connected to said dome, a valve between said dome and hood, a foraminous cage within said still, a shaft projecting through said cage, one of said shaft ends being journaled to slide in the wall of 35 the still, and means for revolving said cage and permitting it to be moved laterally out of the still upon the sliding shaft, substantially as described.

ELMER E. HAND.
